SMOKE PURIFIER FOR TOBACCO SMOKING
ARTICLES

Francis H. Cullen, Philadelphia, Pa.

Application August 29, 1936, Serial No. 98,542

18 Claims. (Cl. 131—173)

The invention relates to a smoke purifier for tobacco smoking appliances for purifying the smoke entering the mouths of smokers. The general broad object of the invention is to provide a tobacco smoke purifier which is simple in construction and efficient in operation and which depends upon water or other liquid as the sweetening, condensing, cooling or purifying agent, and which requires no moving parts for operation. The device may be a part of a tobacco pipe, may be attached to a tobacco pipe, or may be used as a cigar or cigarette holder.

In the past, where water has been used to purify the smoke entering the smoker's mouth, the practice has been to use a purifier consisting of a tobacco bowl set upon an air tight vessel partially filled with water, with a small tube connected to the tobacco bowl, which passes down into the water and a long flexible smoking tube or stem inserted in the side or top of the vessel above the water line. By exhausting the air in the top of the vessel the smoke is forced down through the water and upon entering into the space above it passes into the flexible tube or stem. This apparatus, besides being expensive, is cumbersome and generally may be used only for "home purposes". Improvements of the "old style water pipe" consists of complicated mechanism and traps to prevent leakage.

An object of this invention is to provide a device, the functioning of which depends upon the operation of physical laws relating to the behavior of a liquid in a container, that is, liquid has a tendency to roll along the inner side of the container when it is in a horizontal position and twisted in the hands of an individual. Of course in utilizing the liquid in the container for sweetening, condensing, cooling and purifying the smoke from a tobacco bowl, cigar or cigarette, provision is made that in the event the container is inverted or tilted, the inner tubes which direct the smoke in and out of the container have openings properly spaced and sealed so that the liquid does not leak out.

Therefore, the invention contemplates a tobacco smoke purifier which comprises a body made of wood, glass, laminated substances or other suitable material, which body contains a condensing chamber and a discharge chamber with tubes in the center for directing the smoke, all of which are connected by a restricted passage, the parts so formed that the passage is normally closed to the smoke by a liquid seal. When held in the mouth of a smoker, the induction tube from the tobacco chamber, instead

of extending into the water, as in the "old style water pipe", sets above the liquid, the successful operation depending upon the volume of liquid held by the purifier (the volume can be determined by a measuring device which forms a part of the purifier) and the air space in the discharge chamber being sufficient so that the liquid is not sucked into the smoker's mouth, the openings in the tubes sufficiently spaced, and the ends of the tubes nearest the openings sealed, so that regardless of the position of the liquid held in the purifier it will not leak back to wet the tobacco or enter the smoker's mouth. The shape may be as in Fig. 1, that is, the purifier is curved in order that it may hold a tobacco bowl (which may be fastened, screwed or plugged in with a cork holder or other material to prevent leakage) or it may be horizontal as shown in Figs. 2 and 3 for insertion into a tobacco pipe or for holding a cigar or cigarette. As may be observed from Fig. 1, the smoke passes down through the liquid seal and it also does likewise in Figs. 2 and 3 because the draft created by the smoker causes the smoke to reverse itself so that it passes down through the liquid seal and out into the discharge chamber. In either shape, part of the liquid rests in both the condensing and discharge chambers and the purifier, if twisted in the hands of an individual, the liquid will roll along the inner side, depending upon how it is held.

In the case of Fig. 1, if all of the liquid should be in the condensing chamber, such liquid would roll along the inner side of the condensing chamber. As would be expected, when this shape of purifier is inverted, the liquid allowed to set in the condensing chamber would have a tendency to sweeten and cool the tobacco bowl. In the case of Figs. 2 and 3, at no time would all of the liquid rest in either the condensing chambers, the same as in Fig. 1. As for the small quantity of liquid held in the condensing chamber, the liquid would roll when the purifier is twisted and if the purifier is tilted or inverted, proper spacing of the openings and seal would prevent the liquid from leaking out.

Another object of the invention is the provision of a tobacco smoke purifier which is light in weight so that when attached to a tobacco pipe it does not materially increase its total weight.

Another object of the invention is the provision of a tobacco smoke purifier which is small in size so that when attached to a tobacco pipe it does not materially increase its size.

Another object of the invention is the provision of a tobacco smoke purifier in which the pas-

55

sages are open and clear without possibility of air binding, clogging or blocking the operation of the device.

Another object of this invention is the provision of a tobacco smoke purifier without moving parts, which is readily used and requires little or no attention, except the occasional cleaning of the tubes, by the use of a tobacco pipe cleaner.

Another very important object of the invention is the provision of a measuring device that is attached and which forms a part of the tobacco smoke purifier, its function being to indicate the volume of water or other liquid that is to be held by the tobacco smoke purifier.

Also another very important object of the present invention is the visibility of a tobacco smoke purifier (which may be made of glass or transparent laminated plastic material) so that the smoker may see the operation of the device and from the discoloration of the liquid know when to change the liquid in the purifier.

The device and method have been employed with success using water and other liquids and the invention therefore is described with particular reference to this use.

The liquid sealed restricted opening illustrated in Fig. 1 can be formed by the use of a tube but this is not so desirable because the purifier would be unnecessarily increased in size due to the length of the tube and the air space required in the discharge chamber.

With the above and other objects in view, this invention consists of the details of construction and combination of elements hereinafter set forth and then specifically designated by the claims.

In order that those skilled in the art to which this invention appertains may understand how to make and use the same I will describe its construction in detail, referring by numerals to the accompanying drawing, forming a part of this specification, in which:

Fig. 1 is a longitudinal sectional view of a tobacco pipe illustrating one construction utilizing the principles of my invention.

Fig. 2 is also a longitudinal sectional view of a pipe stem which may be connected to a pipe bowl and constructed according to this invention but slightly modified from Fig. 1.

Fig. 3 is a longitudinal section of the body or stem structure showing a socket for use as a cigar or cigarette holder.

Fig. 4 is a similar view of the mouth piece and component parts.

Fig. 5 is a section on the line 5—5 of Fig. 1, looking in the direction of the arrows.

In carrying out my invention as herein embodied, reference being first had to Figs. 1 and 5, the numeral 10 represents an outer or pipe bowl having a stem body 11 with a large bore communicating with the interior of the pipe bowl 10 through a restricted opening or hole 12. This opening or hole can be formed by a tube. A mouth piece 13 is removably mounted in the outer end of the stem body 11 and has a bore 14 therethrough for the passage of smoke as is usual.

The mouth piece 13 carries a tube 15 projecting from its inner end, which tube extends a suitable distance into the large bore of the stem body 10 and occupies approximately the longitudinal center thereof. This tube 15 is of less length than the stem body and has a larger tube or cylinder 16 on its inner end, said cylinder 16 preferably engaging an end wall to close the open end 75 of the cylinder when the apparatus is assem-

bled. The tube 15 and the cylinder 16 forms a discharge chamber 17 between them and the walls of the stem body 11, which chamber communicates with the interior of the pipe bowl 10 through the opening 12 and with the passageway in the tube 15 through an orifice 18 intermediate the ends of said tube and the inner end of said tube is closed. The closure may be produced in any suitable way but for purposes of illustration such closure is shown as a plug 19 inserted in the tube beyond the orifice 18.

The tube 15 and cylinder 16 may be produced in any desirable way, that is, they may be made from a single piece of material or former separately and joined together. They may be assembled on the mouth piece 13 in any manner that brings the tube 15 into communication with the bore 14 of said mouth piece.

A quantity of water or other liquid 20 is placed in the chamber 17 and occupies some of the space or condensing chamber within the lower part of the pipe bowl 10 to seal the opening 12.

To prevent the tobacco from coming in contact with the liquid seal 20, an inner or tobacco bowl 21 is mounted inside of the pipe bowl 10, and said tobacco bowl 21 is smaller than the pipe bowl to provide a space 22 surrounding the tobacco bowl 21. Said tobacco bowl has an induction tube 23 into which a hole 24 enters from the bottom of the tobacco receiving chamber in the bowl 21 with lateral openings 25 forming communications between the hole 24 and the exterior of the induction tube 23 or the interior of the pipe bowl 10.

The cylinder 16 is used as a measure to gauge the amount of liquid 20 to be placed in the purifier and when a quantity of the liquid equal to the capacity of said cylinder is in the purifier, the opening 12 is liquid sealed at such times as the pipe is held in a substantially horizontal position or in an inclined position as illustrated. As the user induces a draft through the pipe the smoke will follow the directions of the arrows and flow from the tobacco bowl 21 through the hole 24 and openings 25 into the pipe bowl 10, thence through the restricted opening 12 and its liquid seal, the chamber 17, orifices 18, the tube 15 and the bore of the mouth piece 13. During the passage of the smoke through the liquid seal said smoke will be purified, cooled and sweetened thus producing a satisfying flavor.

Because of the provision of the induction tube 23 and the openings 25 an inconsequential amount or none of the liquid sealing agent will enter the tobacco bowl when the pipe is shaken or even inverted and when tilted or inverted the liquid will occupy the space 22 or the chamber 17 or both and will not spill out and so the pipe can be carried in a pocket or pouch without fear of losing the liquid or soiling the clothes. Any of the liquid in the chamber 17 will roll along the inner surfaces of the chamber walls and is unlikely to enter the tube 15 but because the orifices 18 are directly opposite each other should some of the liquid pass into one orifice it generally will pass right through the other orifice.

The modification illustrated in Figs. 2, 3 and 4 includes a stem body 26 with an apertured connector 27 at one end and a mouth piece 28 at the other end, the latter preferably being removably attached to the stem body and has a bore 29 running longitudinally therethrough. The connector 27 may be separate from the stem body 26, as shown, or obviously it may be an integral part thereof and it may be in the form of a plug, 75

Fig. 2, for insertion in a pipe bowl 30 or fashioned as socket to receive a cigar or cigarette, Fig. 3.

An induction tube 31 is carried by the inner 5 end of the connector and is located wholly within in the stem body occupying the longitudinal center thereof. Surrounding the intermediate portion of the induction tube 31 and carried thereby is a cylinder 32 open at its outer end and closed 10 at its inner end except for a restricted opening 33. The induction tube and cylinder may be formed from the same piece of material, as shown, or separate parts fastened together as will be obvious. Said induction tube 31 has oppositely 15 disposed orifices 34 located between the closed end of the cylinder and preferably outside of the cylinder 32 so that access may be readily had to them for cleaning purposes.

A tube 35 is carried by and projects from the 20 inner end of the mouth piece 28 and the interior of said tube communicates with the bore of said mouth piece. The inner end of the tube 35 is closed in any suitable manner, as by a plug 36 but has oppositely disposed orifices 37 to provide 25 communications between the interior and exterior of said tube. A cylinder 38 is carried by the inner end of the tube 35 and is closed at its outer end where it joins with the tube and open 30 at its inner end. The cylinders 32 and 38 telescope, one over the other, and for purposes of illustration, the cylinder 38 is shown large enough to fit over the cylinder 32. When the parts are assembled the outer end of the induction tube 31 will be closed as well as the inner 35 end of the tube 35 and the combining of the two cylinders will produce an inner chamber 39 and an outer chamber 40.

A quantity of liquid which will reach to an 40 approximate level 41 when the appliance is held in an inclined position, as shown in Fig. 2, is placed in the outer chamber 40 and forms a liquid seal for the restricted opening 33. The parts of the apparatus should be so proportioned and the quantity of liquid should be such that 45 said restricted opening 33 will be sealed by the liquid sealing agent even though the device is held in an approximately horizontal position.

Due to the staggered relation of the orifices 34 and 37 and the restricted opening 33 relative to 50 each other the sealing liquid is unlikely to pass into the tubes and therefore will be retained regardless of the position of the appliance when not in use.

While employed for smoking purposes a draft 55 will be induced through the appliance and tobacco smoke will flow through the apertured connector 27, induction tube 31, orifices 34, chamber 33, restricted opening 33, chamber 40, orifices 37, tube 35 and the bore 29 of the mouth piece. As 60 the smoke travels this circuitous route it will pass through the liquid seal and be sweetened, condensed, cooled and purified before reaching the smoker's mouth.

The walls of the chambers holding the liquid 65 seal can be of glass or laminated material so that the operations will be visible. The parts can be readily and easily disassembled for cleaning purposes and when the mouth piece with its component elements are disconnected from the stem body, the cylinder 38 can be used to measure the quantity of water or other liquid sealing agent to be placed in the chamber 40.

Of course I do not wish to be limited to the 70 exact details of construction herein shown and described as these may be varied within the

scope of the appended claims without departing from the spirit of my invention.

Having thus described my invention, what I claim as new and useful is:

1. In a smoke purifier of the kind described, a 5 pipe bowl, a tobacco bowl of less depth than the pipe bowl and its lower part of smaller diameter than said pipe bowl and insertable in the latter leaving a space between the two bowls, an induction tube on the bottom of said tobacco bowl 10 with a hole therein communicating with the interior of the tobacco bowl and lateral openings from the hole to the exterior of the induction tube, a hollow stem body carried by the pipe bowl in communication with the latter through a restricted opening adapted to be sealed by a liquid sealing agent, a mouth piece having a longitudinal bore and insertable in the outer end of the stem body, a tube carried by said mouth piece and communicating with the bore thereof, said 20 tube having oppositely disposed orifices intermediate its ends and the inner end of said tube being closed, and a cylinder carried by said tube having an open inner end adjacent a wall at the inner end of the stem body, said tube and cylinder occupying the longitudinal center of 25 said stem body.

2. In a smoke purifier, a stem body, a connector carried by one end of said stem body, a tube carried by said connector and projecting into 30 the stem body, a cylinder having a closed outer end carried by the tube and surrounding an intermediate portion of said tube, said cylinder having a restricted opening in the region of its closed end adapted to be sealed by a liquid sealing agent and said tube having oppositely disposed orifices contiguous to the open end of said cylinder, a mouth piece with a longitudinal bore carried by the opposite end of the stem body, a tube carried by said mouth piece and communicating with the bore thereof and projecting into the stem body, said tube having oppositely disposed orifices intermediate its ends and the inner end thereof closed, and a cylinder carried by 35 the last named tube and telescoping with the first mentioned cylinder, the assembly of the parts closing the inner end of the first named tube.

3. A smoke purifier for tobacco smoking appliances consisting of a housing containing a 40 condensing chamber and a discharge chamber between the tobacco holding chamber and mouth end of a smoking appliance with a restricted opening from the condensing chamber to the discharge chamber sealed with a liquid sealing agent, and an induction tube having an open end, a closed terminal end and a lateral port outlet, the open end of said induction tube being in communication with the tobacco chamber, and the lateral port outlet being contained within and 45 enclosed by the condensing chamber.

4. A smoke purifier for tobacco appliances consisting of a housing containing a condensing chamber and a discharge chamber between the tobacco holding chamber and mouth end of a 50 smoking device, with a restricted opening from the condensing chamber to the discharge chamber, and an induction tube having an open end and a closed terminal end and a lateral port outlet, the open end of said induction tube being in 55 communication with the tobacco chamber, and the lateral port outlet being contained within and enclosed by the condensing chamber.

5. In a smoke purifier for tobacco smoking appliances consisting of a housing containing a 60

condensing chamber and a discharge chamber between the tobacco holding chamber and mouth end of a smoking appliance with a restricted opening from the condensing chamber to the discharge chamber sealed with a liquid sealing agent, an induction tube having an open end with its opposite terminal closed except for a lateral port adjacent the closed terminal, the open end of said induction tube being in communication with the tobacco chamber, and the closed end with the lateral port being extended into and enclosed by the condensing chamber.

6. A smoking purifier for tobacco smoking appliances consisting of a stem body with a restricted opening between the tobacco holding and mouth ends, said opening being adapted to be sealed by liquid, and a liquid measuring device housed in said stem body and used to determine the proper amount of sealing liquid to be placed in the appliance.

7. A smoke purifier for tobacco smoking appliances consisting of a tobacco holding means projecting into a liquid holding chamber, said tobacco holding means carrying an induction tube with one end open to the tobacco holding means and the opposite terminal end of the induction tube closed except for a lateral port outlet, and a liquid in said chamber for cooling the tobacco holding means.

8. A smoke purifier for tobacco smoking appliances comprising a tobacco holding means, a stem body having its interior in communication with the tobacco holding means through a restricted opening, an induction tube having an open end communicating with the tobacco holding means and its opposite end closed, said induction tube having a lateral port intermediate its ends, a mouthpiece carried by the stem body, a tube projecting from the mouthpiece and extending into the stem body and having a lateral port spaced from the mouthpiece, and a liquid measuring means connected with the inner end of the last named tube.

9. The structure in claim 8, in combination with means coacting with the liquid measuring means to form a condensing chamber.

10. In a device of the kind described, a tobacco smoking appliance having a chamber from which leads a restricted opening, a tobacco holding means, an induction tube having an open end communicating with the tobacco holding means and its opposite terminal end closed, said closed end having a lateral port and projecting into said chamber, and a liquid seal for the restricted opening, a portion of which liquid enters the chamber.

11. In a device of the kind described, a tobacco smoking appliance including a bowl providing a chamber from which leads a restricted opening, a tobacco holding means in the bowl, an induction tube having an open end communicating with the tobacco holding means and its opposite terminal end closed, said closed end having a lateral port and projecting into said chamber, and a liquid seal for the restricted opening, a portion of which liquid enters the chamber to act as a cooling agent for the tobacco holding means.

12. In a smoke purifier, a stem body, a connector carried by one end of said stem body, a tube carried by said connector and projecting into the stem body, a cylinder having a closed outer end and an open inner end carried by the tube and surrounding an intermediate portion of said tube, said cylinder having a restricted opening in the region of its closed end, and said tube

having oppositely disposed orifices contiguous to the open end of said cylinder, a mouthpiece with a longitudinal bore carried by the opposite end of the stem body, a tube carried by said mouthpiece and communicating with the bore thereof and projecting into the stem body, said last named tube having oppositely disposed orifices intermediate its ends and the inner end thereof closed, and a cylinder carried by the last named tube and telescoping with the first mentioned cylinder, the assembly of the parts closing the inner end of the first named tube.

13. A smoke purifier for tobacco smoking appliances consisting of a housing containing a condensing chamber within a discharge chamber and both located between the tobacco holding chamber and mouthpiece of a smoking appliance, said condensing chamber having front and rear and side walls except for a restricted opening from the condensing chamber to the discharge chamber, said opening being located below the longitudinal center of said condensing chamber, an induction tube forming a communication between the tobacco holding chamber and condensing chamber, and an eduction tube forming a communication between the discharge chamber and the mouthpiece.

14. A smoke purifier for tobacco smoking appliances consisting of a housing providing a discharge chamber, an open ended cylinder within the discharge chamber, means to hold and close the outer end of said cylinder, an induction tube forming a communication between a tobacco holding chamber and the interior of said cylinder, an eduction tube forming a communication between the discharge chamber and a mouthpiece, and a closure attached to said eduction tube and coacting with the inner end of the cylinder to close said cylinder except for an opening leading to the discharge chamber.

15. A smoke purifier for tobacco smoking appliances consisting of a housing providing a discharge chamber, an eduction tube forming a communication between said discharge chamber and a mouthpiece of the smoking appliance, a cylinder having a closed inner end and supported by the eduction tube and also having an open outer end, an induction tube forming a communication between a tobacco holding chamber of the smoking appliance and the interior of the cylinder, and means to close the open end of the cylinder thereby providing a condensing chamber which has an opening leading to the discharge chamber.

16. A smoke purifier for tobacco smoking appliances consisting of a stem body with a restricted opening between the tobacco holding and mouth ends, said opening adapted to be sealed by liquid, and a liquid measuring device inserted in the draft passageway and housed in said stem body and used to determine the proper amount of sealing liquid to be placed in the appliance.

17. A smoke purifier for tobacco smoking appliances consisting of a stem body provided with a discharge chamber between the tobacco holding and mouth ends, a cylindrical member closed at one end and open at the opposite end and disposed within the discharge chamber and adapted to be used as a measuring device to determine the proper amount of sealing liquid to be placed in the appliance, and means with which said cylindrical member cooperates to close the open end thereof and provide a condensing chamber with an opening between said condensing and

discharge chambers adapted to be sealed by the sealing liquid.

18. A smoke purifier for tobacco smoking appliances consisting of a stem body having a discharge chamber, a condensing chamber within the discharge chamber and having an open and a closed end, means for supporting the outer

closed end of said condensing chamber and a cylindrical cap for closing the inner open end of the condensing chamber, said condensing chamber having an opening leading therefrom to the discharge chamber.

FRANCIS H. CULLEN.
